UNITED STATES PATENT OFFICE.

SIDNEY GEORGE BROWN, OF LONDON, ENGLAND.

SUBMARINE-CABLE TELEGRAPHY.

965,368.

Specification of Letters Patent. Patented July 26, 1910.

Application filed September 10, 1907. Serial No. 392,108.

To all whom it may concern:

Be it known that I, SIDNEY GEORGE BROWN, a subject of the King of Great Britain, residing at 4 Great Winchester street, 5 in the city and county of London, England, electrical engineer, have invented certain new and useful Improvements in or Relating to Submarine-Cable Telegraphy, of which the following is a specification.

10 This invention relates to submarine cable telegraphy, and has for its object to increase the speed in connection with the transmitting and receiving of signals, and generally to improve the working of such systems.

15 By my invention I am enabled to utilize for signaling purposes, not only the quick changing or signaling currents as they are called, but also the slow discharge currents which are due to the charging up action of 20 the cable when a succession of signals of the same sign are transmitted.

Hitherto it has been found necessary to prevent the discharge currents from passing into the receiving instrument, and the 25 present invention consists of means whereby it is possible to utilize such currents, in such a manner that a signaling speed from 50 per cent. greater than the present rate may be obtained.

30 When signals are sent into a line, two types of current impulses namely the signaling or quick changing currents and the slower discharge currents from the cable, arrive, at the receiving end of the line. If 35 for example a cable be directly connected to a recorder without the intervention of a blocking condenser, or other equivalent arrangement for preventing the discharge currents from flowing through the instrument, 40 a succession of signals of the same sign arriving at the recorder, will produce a current through the coils of the recorder, which increases rapidly at first, and then less rapidly, and finally tends to a constant value 45 producing a curve on the tape somewhat like the curve A, in Figure 1 of the accompanying drawings. The effect of interposing a blocking condenser at the receiving end, will be to eliminate the slowly rising 50 discharge current, and only permit the variations of the said current to arrive. The result will be a curve such as B, Fig. 1, in which the ordinate is roughly proportional

to the rate of change of the ordinate of curve A. Such a curve is called a quick changing 55 or signaling current. The curve A is called a slow, or discharge current.

Up to the present time it has been considered necessary to prevent the discharge current from flowing through the receiving 60 siphon recorder or relay, by means of a condenser in series with the receiver, or in other equivalent way. Now an inspection of the curves in Fig. 1 will show (what is of course well known) that the action of the condenser 65 while it sharpens the signals, at the same time largely reduces the amplitude of the arrival currents, and consequently the power available to operate the receiving instrument. I have discovered that by the application 70 of the means hereinafter described, it is possible to utilize a considerable proportion of the so-called discharge current, as well as the signaling current to operate the recorder or relay. I therefore permit 75 the proper proportion of the discharge current to pass through the receiving instrument by increasing the capacity of the series blocking condenser, by shunting such condenser with a resistance, by increasing the 80 induction of a magnetic shunt across the instrument, by increasing the resistance in series with such shunt, or in any other suitable way.

For the purpose of my invention there 85 may be an automatic transmitter, operated by a sending battery of the kind usually employed. The receiving instrument is a relay, preferably of the type described in my British Letters Patent No. 1434 of 1899, the 90 tongue being preferably of the character described in my British Letters Patent No. 12,500 dated 29th May 1906. The relay tongue is adapted not only to operate a direct writer for recording the signals and the 95 sending-on relays, as heretofore, but also controls the current in a local branch circuit, hereinafter called the "reaction circuit," in which is included a subsidiary coil on the relay, so arranged that when the tongue 100 makes contact with one of the surfaces of the drum of the relay, a current is caused to flow through the circuit and the subsidiary coil on the relay, in such a direction that it tends to move the tongue to the side of the 105 drum opposite to the contact which supplied

the current in the said circuit, thereby producing a counteracting force which determines the delineation of the signals.

In order that my invention may be clearly understood and carried into effect, I will proceed to describe the same with reference to the further diagrams represented in the annexed drawings, Fig. 1 being a diagram showing the curves produced on the tape by the slowly rising discharge current and the quick changing or signaling current; and Fig. 2 being a diagrammatic view of an arrangement of apparatus adapted to accomplish the objects of my invention, and Fig. 3 a diagram illustrating the shape of the current wave resulting from my improved mode of working, compared with the shape of the current wave which would be obtained without the counteracting force, and also illustrating the manner in which the signals are emphasized and perfected.

According to the arrangement illustrated in Fig. 2, the apparatus may comprise a line wire A, with a receiving condenser n , which is shunted with a suitable resistance n^1 . The line wire is in operative connection with the coil a of the relay, so as to operate the tongue a^1 arranged to move across the surface of the revolving drum which is provided with contact surfaces a^2 , and an insulated portion a^3 . The said drum may be in connection with the ordinary sending-on post office relays a^4 , a^5 , which, when used, are disposed in the circuit of a split battery b , the aforesaid circuit being connected with the contact surfaces a^2 of the drum by leads b^1 . Condensers b^2 of suitable capacity are arranged across the contact between the tongue a^1 and the contact surfaces a^2 of the drum. From the mid point of the battery b a lead b^3 is taken to a direct writer or recording instrument c , thence through the lead b^4 and the reaction circuit e to the tongue a^1 of the relay. The reaction circuit e is a divided circuit, containing in one arm a non-inductive resistance e^2 , and in the other arm an inductive resistance e^1 and the auxiliary coil d wound on the relay coil a . By suitable adjustments of the coils e^1 and e^2 it is possible to determine the magnitude of the current wave through the coil d , as well as its time-period and shape. It is thus possible to adjust accurately the magnitude and the time effect of the counteracting force exerted on the tongue of the relay, when it is moved into or out of contact with one of the contact surfaces of the drum. The sign of the correcting force is always such that its tendency is to move the relay tongue back toward the insulating strip.

I will now proceed to describe the effect on the signals produced by the employment of the methods of working which are the subject of this invention. Referring to Fig.

move to the middle of no-man's-land at the point 8.

It will be seen that, in a series of reversals, such as occur in connection with the letter C provided the speed of signaling is high enough, only the first and last of such reversals arrive. The intervening reversals are wiped out but not so the beginning and the end signals due to the result of their being only partially neutralized by a single following and preceding reversal respectively. Under these conditions the current from the cable can start and stop the current in the reaction circuit which operates to put 10 in the reversals as though they had actually arrived from the cable.

In the case of a combination of signals of the same polarity, as in the letter H, the curbing of these signals having been reduced 20 as aforesaid, the current from the cable will accumulate or rise to a point indicated at 9, but as the reaction circuit is opposed to this as represented by the line B, the movement of the tongue on the drum will be according to the curve indicated by the dotted line at the point 10; on the current falling 25 to the point 11, the reaction circuit brings the tongue on to the insulated portion X or no-man's-land, of the drum, at the point 12, 30 representing a space between the signals as is the case at the point 8 between C and H. In the case of a single signal of the same polarity as the last signal following this space as in the case of the letter E, the current from the cable will rise to the point 13 35 on the curve but not so high as in the combination of signals representing the letter H. The effect of the reaction circuit in this connection will be to bring the curve to the point 40 14, on the insulating portion X representing another space. In the case of the combination of signals of different sign as in the letter A, the reaction circuit will assist the current to make the signaling contacts at 45 points 15 and 16, bringing the tongue promptly back to the insulating portion of the drum at the point 17.

The advantages of this method of working will now be obvious, for it is possible 50 to obtain signals of much greater amplitude than heretofore and still retain perfect definition. The practical result of this is that it is possible to largely increase the rate of signaling with a given cable.

55 It will be found that there is no difficulty in so adjusting the constants of the reaction circuit, as to give the best results, especially if the resistance, in one arm, and the inductance in the other arm, are made so that they 60 are conveniently and readily adjustable. In order that there may be no difficulty in carrying the invention into effect, it may be stated, by way of example, that on a cable of say 3.2KR such as that between Gibralter

and Porthcurnow the magnetic bridge *m* 65 may have an inductance of 7.32 henries, while the resistances *m*¹ and *m*² may each have a value of 1 ohm. The receiving condenser *n* may have a capacity of about 80 microfarads, while the condenser *o* may have 70 a capacity of 7 microfarads. The condensers *b*² may each have a capacity of 4 microfarads. Each half of the dry battery *b* may be composed of 4 dry cells. The resistance of the direct writer or sending on instrument *c* may be 500 ohms. The resistance *e*² 75 may be of about 20 ohms and the inductance of *e*¹ may be of about 1.8 henries. The resistance of the coil *d* may be about 60 ohms.

It will of course be understood that the 80 diagrams herein referred to which are of a theoretical character are intended as examples of the manner of applying the invention and for the purpose of explaining the invention in connection with submarine 85 telegraphy. Also that although in the foregoing an example of the application of the invention to a duplex system of telegraphy is illustrated and described, the invention may be readily applied in connection with 90 other systems in which the cable code is employed.

What I claim and desire to secure by Letters Patent of the United States is:—

1. In a system for receiving signals from 95 a cable in cable code the combination with a receiving instrument of means for enabling the discharge currents to be utilized to give amplitude to the signals and a suitably adjusted reaction circuit for modifying such signals to receive increased definition.

2. In a system for receiving signals from a cable in cable code the combination with a relay of a series blocking condenser, a resistance shunting such condenser, a magnetic shunt across said relay, a resistance in series with such shunt and a reaction circuit which acts differently upon the three classes of signals, namely, reversals, consecutive 105 signals of the same sign, and single signals whereby it is possible to utilize the discharge current from the cable and at the same time secure increased definition in the signals.

3. In a system for receiving signals from a cable in cable code the combination with a relay of means for enabling the discharge currents to be utilized to give amplitude to the signals and a suitably adjusted reaction 110 circuit for modifying such signals to receive increased definition.

4. In a system for receiving signals from a cable in cable code the combination with a receiving instrument of a series blocking 120 condenser, a resistance shunting such condenser, a magnetic shunt across said receiving instrument, a resistance in series with

such shunt and a reaction circuit which acts differently upon the three classes of signals, namely, reversals, consecutive signals of the same sign, and single signals whereby it is possible to utilize the discharge current from the cable and at the same time secure increased definition in the signals.

In testimony whereof I affix my signature in presence of two witnesses.

SIDNEY GEORGE BROWN.
